UNITED STATES PATENT OFFICE.

PHILIP SCHWICKART, OF BROOKLYN, NEW YORK.

DESIGN FOR A LENS FOR VAULT-LIGHTS.

SPECIFICATION forming part of Design No. 23,348, dated June 12, 1894.

Application filed April 25, 1894. Serial No. 509,028. Term of patent 14 years.

To all whom it may concern:

Be it known that I, PHILIP SCHWICKART, a citizen of the United States, residing at Brooklyn, in the county of Kings and State of New York, have invented and produced a new and original Design for a Lens for Vault-Lights, of which the following is a description.

Reference is to be had to the accompanying drawings, forming a part of this specification, in which similar letters of reference indicate corresponding parts in both the figures.

Figure 1 is a perspective view of a lens for vault lights showing my design; and Fig. 2 is a sectional side elevation of the same.

The leading feature of my design consists in a lens for vault lights, provided with a rounded off protuberance A in the center of the arched top B of the said lens.

I claim—

The design for a lens for vault lights as herein shown and described.

PHILIP SCHWICKART.
